UNITED STATES PATENT OFFICE

171,623

CASING FOR AN AMUSEMENT GAME APPARATUS

Harry L. Skelly and Edith Freedman, Reno, Nev.

Application August 17, 1953, Serial No. 26,488

Term of patent 14 years

(Cl. D34—5)

To all whom it may concern:

Be it known that we, Harry L. Skelly and Edith Freedman, citizens of the United States, both residing at Reno, county of Washoe, and State of Nevada, have invented a new, original, and ornamental Design for Casing for an Amusement Game Apparatus, of which the following is a specification, reference being had to the accompanying drawing, forming a part hereof.

Figure 1 is a front perspective view of a casing for an amusement game apparatus showing our new design;

Figure 2 is a back perspective view thereof;

Figure 3 is a perspective view of the design showing one side; and

Figure 4 is a perspective view of the design showing the side opposite that shown in Figure 3.

We claim:

The ornamental design for a casing for an amusement game apparatus, substantially as shown.

HARRY L. SKELLY.
EDITH FREEDMAN.
